US0D1056916S

(12) **United States Design Patent** (10) Patent No.: **US D1,056,916 S**
(45) Date of Patent: ** Jan. 7, 2025

(54) **SCANNER**

(71) Applicant: **PFU Limited**, Kahoku (JP)

(72) Inventors: **Motoshi Shibuya**, Kahoku (JP);
Satoshi Kuroda, Kahoku (JP); **Ryuichi Nagai**, Kahoku (JP); **Kengo Matsuda**, Kahoku (JP); **Kengo Kadoya**, Kahoku (JP)

(73) Assignee: **PFU Limited**, Ishikawa (JP)

(**) Term: **15 Years**

(21) Appl. No.: **29/884,697**

(22) Filed: **Feb. 15, 2023**

(30) **Foreign Application Priority Data**

Oct. 14, 2022 (JP) ..... 2022-022313 D
(51) **LOC (15) Cl.** **14-02**

(52) **U.S. Cl.**
USPC **D14/422**

(57) **CLAIM**

The ornamental design for a scanner as shown and described.

DESCRIPTION

FIG. 1 is a perspective view of a scanner showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof, and,

FIG. 7 is a bottom plan view thereof.

The broken lines in the figures depict portions of the scanner that form no part of the claimed design.

1 Claim, 7 Drawing Sheets
